UNITED STATES PATENT OFFICE.

ROSS McCOY, OF ALAMEDA, CALIFORNIA.

DESIGN FOR A GASOLINE SERVICE STATION.

Application filed June 11, 1928. Serial No. 27,088. Term of patent 14 years.

To all whom it may concern:

Be it known that I, Ross McCoy, a citizen of the United States, residing at Alameda, county of Alameda, and State of California, have invented a new, original, and ornamental Design for a Gasoline Service Station, of which the following is a specification, reference being had to the accompanying drawing, forming part thereof.

The figure is a perspective view of a gasoline service station, showing my new design:

I claim:

The ornamental design for a gasoline service station, as shown.

ROSS McCOY.
